UNITED STATES PATENT OFFICE.

FRED H. REAM, OF KANSAS CITY, MISSOURI.

METAL BRIDGING FOR FLOOR-JOIST.

1,106,845.

Specification of Letters Patent. Patented Aug. 11, 1914.

Application filed July 2, 1913. Serial No. 777,068.

To all whom it may concern:

Be it known that I, FRED H. REAM, a citizen of the United States, residing at Kansas City, in the county of Jackson and 5 State of Missouri, have invented a new and useful Improvement in Metal Bridging for Floor-Joist, of which the following is a specification.

My invention relates to metal-bridging for 10 floor-joist, of the class shown and described in my application for Letters Patent of the United States, filed February 27, 1913, Serial No. 751,078, by means of which floor-joist are braced and trussed to carry com- 15 pression and tension strains.

The objects of my invention are: First, to provide a cheap, substantial and durable bridging-member, formed integral of a single strip of metal; second, to provide shoulders adjacent the middle of the bridging-member, adapted to bear against the sides of the joist, each of which shoulders is provided with a pointed prong, adapted to be forced into the joist, to retain the bridging-member in place; third, to provide pointed prongs on the opposite ends of the bridging-member, adapted to pierce the joist, to reinforce the fastening devices in the top of the joist; and fourth, to provide a hole, apertured through one end of the bridging-member, adapted to be engaged by a lever, to draw the bridging-member to place when applying the same to floor-joist. These, and other objects, will appear in the following 35 description, it being understood that changes in form, proportion and minor details of construction may be resorted to, within the scope of the appended claims. I attain these objects by the construction and ar- 40 rangement of parts, illustrated in the accompanying drawing, in which:

Figure 1. is a sectional view of a floor, supported by floor-joist, provided with my invention. Fig. 2. is a side elevation of my 45 invention, partly sectioned, and illustrating the method of applying the bridging-member. Fig. 3. is a plan view of my invention. Fig. 4. is a sectional view of a part of my invention, on the line I, I, in Fig. 5. Fig. 5. 50 is a vertical elevation of a part of my invention, showing the prong integral with the shoulder; and Fig. 6. is a plan view of a modified form of the prong, formed on the end of the bridging-member.

Similar reference numerals refer to corresponding parts throughout the drawing. 55

The numeral 1 indicates my improved bridging-member, which I preferably make from a strip of sheet metal, such as iron and steel, preferably galvanized iron, and which 60 is of a length adapted to extend from the bottom of one floor-joist to the top of the two next adjoining floor-joist. A hole 2 is centrally apertured in the strip intermediate its length, and a hole 3 is apertured in the 65 strip adjacent opposite sides of the hole 2. The apertures are provided for the entry of fastening devices 4, which pierce the bridging-member and the lath or boards used in providing a ceiling. The ter- 70 minal ends of the strip are each provided with pointed prongs 5, 5, and 6, 6, the tips of which are bent downwardly, to an angle a little in excess of a right angle, and adapted to be forced into the side of the floor 75 joist, as shown at 7, 7, in Fig. 2. A hole 8 is apertured in the strip, adjacent its one end, rearwardly of the prongs 6, through which hole a lever 9 is extended, to bear against the adjacent side of the joist, this 80 provision enabling the bridging-member to be drawn to bear snugly upon the under edge of the joist resting on the middle of the bridging-member, after the opposite end of the bridging-member has been secured to 85 the joist, as shown in Fig. 2. A plurality of small openings 10 are apertured in the strip, adjacent its opposite ends, through which 90 fastening devices 11, such as nails, screws and the like, may engage the top of the joist. 90

From adjacent the middle of the strip, lengthwise considered, to adjacent the apertures 10, on both sides of the middle, the strip is indented and formed in angular shape, as shown at 12, in Fig. 3, for the pur- 95 pose of providing rigidity to the portions of the bridging-member involved in the operation mentioned, the ends of the angular indentation being slanted, to provide the shoulders 13, 13, adjacent the middle of the strip, and the shoulders 16, 16, adjacent the terminal portions of the same, which shoulders 13, 13, are adapted to vertically bear against the adjacent sides of the joist, when the bridging-member is bent upwardly on 100 each side of its middle portion, to form upwardly-extending arms 14, 15, and bringing the shoulders 16, 16, formed adjacent 105

the upper ends of the arms, to bear against the bottom of the floor, as shown in Fig. 1. The portion of the strip outwardly from the shoulders 16, 16, on both upwardly-extending arms 14, 15, is bent outwardly, to substantially lie in a plane parallel with the floor. A pointed prong 17 is formed integral with each of the shoulders 13, 13, the point of which is bent upwardly to an angle 10 a little in excess of a right-angle, and adapted to be forced into the joist, when the shoulders 13, 13, are bearing against the joist, and for the purpose of retaining the bridge-member in place prior to the fastening 15 of the ends of the arms to the next adjoining joist, on both sides, the ends of the arms are fastened at the time the floor is laid, and as effectively as if the shoulders had been pierced by nails or other fastening 20 devices penetrating the joist. The prongs 17 are formed in the face of the shoulders 13, 13, by a triangular incision through their respective faces, the point of the prong being bent forwardly and downwardly, as 25 shown in Fig. 5.

To apply my bridging-member, the middle portion of the bridging-member is placed to bear against the under edge of the joist 19, the shoulders 13, 13, on the opposite arms bearing against opposite sides of the joist, and the outwardly-bent end of the free arm 15 bearing upon the top edge of the next adjoining joist 20. The lever 9 is extended through the hole 8, to and against 30 the outside of the adjacent joist 20, and a pressure is outwardly applied to the lever 9, thus drawing the bridging-member tightly to place, thus securely retaining the adjustment obtained. The overhanging portions of the arms are then bent down against the outer side of the joist, and the prongs 6, 6, forced to pierce the sides of the joist. A

bridging-member is similarly secured to each floor-joist, when the floor is laid in the customary manner.

The bridging-member is adapted to be applied without nails or fastening devices of any kind, excepting the prongs carried by the bridging-member, as above described. The bridging-member is formed integral throughout, providing in one single member facilities for its application to floor-joist, to effectively carry all compression and tension strains.

What I claim is:

1. In a joist bridging, a metal bridge member consisting of a strip of metal formed with an upwardly extending arm outwardly of each side of the middle of the strip, each of said arms being provided longitudinally 60 with a triangular shaped rib having its opposite ends beveled, the lower beveled end of each rib being provided integrally with a pointed prong extending outwardly substantially at right angles to said end of the 65 rib.

2. In a joist bridging, a metal bridge member consisting of a strip of metal formed with an upwardly extending arm outwardly of each side of the middle of the strip, each of said arms being provided longitudinally 70 with a tri-angular shaped rib having its opposite ends beveled, the lower beveled end of each rib being provided integrally with a pointed prong extending outwardly substantially at right angles to said end of the 75 rib, in combination with a pointed prong integral with each of the terminal ends of the bridge members.

FRED H. REAM.
